Specification of Letters Patent.

Patented July 16, 1918.

Application filed August 16, 1913. Serial No. 785,066.

To all whom it may concern:

Be it known that I, JESSE JEFFERS, a citizen of the United States, residing at Whitinsville, Massachusetts, have invented 5 the following described Improvements in Quillers.

The invention relates to apparatus for facilitating the doffing and general operation of quilling machines and comprises an over- 10 traverse mechanism or device connected with the thread guide frame, or the traverse mechanism thereof, whereby such frame may be temporarily depressed below its normal range of traverse so as to cause the yarn 15 or thread to be wrapped around the spindle collar below the base of the quill, thus serving as a means for holding the ends while the full quills are removed and fresh ones substituted on the spindles. The in- 20 vention further comprises in combination with such mechanism or device, means whereby the same is rendered normally idle and unaffected by the movement of the traverse mechanism as produced by the 25 builder motion, and whereby the frame may be locked in its depressed position with the thread guides lowered where they will not obstruct the rapid removal and replacement of quills, all as will be apparent to those 30 familiar with this subject and as will be more particularly pointed out in the claims appended hereto.

In the drawings forming part hereof,

Figure 1 is an end view of a quiller with 35 certain parts in rear shown in dotted lines and certain other parts removed, and having the present invention applied to it.

Fig. 2 is a detail of the quiller spindle and thread guide.

Fig. 3 is a detail of the over-traverse 40 mechanism.

Fig. 4 is a diagrammatical illustration of the action of the device and showing a different lever and lock.

Fig. 5 is a modified form, in front elevation.

The quiller frame comprises two similar end standards 1, connected by one or more longitudinal bars or girders 2, and by a 50 series of parallel bolster rails 3, upon which the numerous spindles 4 are journaled. The bolster rails are disposed in steps ranging upward and rearward as shown in Fig. 1 and the quill spindles 4 thereon are belted, 55 by means of tapes, to their corresponding

driving drums 5, to which power is applied in any suitable manner to drive the spindles. A counter-weighted foot-treadle 6 disposed at the front of the machine, and co-extensive with the length thereof, serves to 60 control the power through a belt-shipper or like-device, which also is not shown, being of ordinary or any suitable design. So long as the operative who stands on a step or platform 7, depresses the treadle with her 65 foot, the machine is kept in motion, release of the treadle stopping the machine through the action of the counterweight 6^a. It will be understood that the platform 7 extends 70 the length of the machine as usual, being set close to the foot treadle rail 6 so that the operative can reach the upper rows of spindles.

The thread-guide frame comprises a series of parallel thread-guide rods 8, carried by 75 two or more inclined cross-bars 8^a, in such manner that each rod is adjacent to one of the rows of spindles on the bolster rails 3. Each of the said rods carries a series of thread-guides 20, sufficient to serve all the spindles in 80 the row. The thread guide frame as thus equipped is mounted upon the upper ends of a set of lifter rods 9, which are journaled to slide vertically in the main frame and connected at their lower ends with a series 85 of counter-weighted lifter levers such as shown at 10. The lifter levers are connected with each other by means of a horizontal and endwise moving connecting rod 11, all of the rods and levers being thus caused to 90 move in unison and produce an even rise and fall at both ends of the thread guide frame. The counterweights applied to the traverse mechanism on the lifter levers thereof, or elsewhere, are desirably made sufficiently 95 heavy to overbalance the weight of the lifter rods and guide-frame with its attached parts so that the tendency is for the frame to rise except as otherwise restrained. The lifter lever 10 at one end of the machine is 100 provided with a sector arm 12, to which a chain 13 is attached running thence over a sheave 14 to the regular builder motion which is indicated generally by 15. In the normal operation of the quiller, a cam 16 105 actuates the lever of the builder motion, which in turn reciprocates the builder chain 13 and the rest of the traverse motion, which imparts to the thread guide frame its normal up and down motion appropriate for 110

the length of quills used, and gives it also an appropriate gain motion, as will be well understood, the same being supplied through the operation of the ratchet wheel on the builder as usual, giving any desired character of wind of thread. The builder motion of itself forms no part of the present invention and is therefore not described. It will be understood that its function is to 10 impart a normal traverse motion of any desired character to the thread guide frame such as will properly build the yarn on the rotating quills.

The over-traverse device is applied to the 15 connecting rod 11, above referred to, and in the specific form illustrated by Figs. 1-3 it comprises a lever 18, fulcrumed on a bracket 19 bolted to the outer face of one end standard, and connected by a chain 21 or equivalent flexible means with a sleeve 22, which 20 sleeve is capable of sliding freely on the connecting rod. When the lever 18 is thrown down as indicated, the sleeve is thereby drawn along the rod 11 into contact with a 25 collar 23 fixed on the rod and by means of such engagement moves the rod in a direction to depress the arms of the lifter levers and hence to lower the thread guide frame. The throw of the lever is sufficient to thus 30 move the rod from any position in which it may happen to be when the sleeve strikes the collar, to a point beyond its normal range of downward traverse, which extent of motion will bring all the thread guides to 35 the position represented by the dotted lines in Fig. 2 or of the full lines of Fig. 1 or Fig. 4. The device thus predominates over the builder motion and, when operated, slackens the builder chain 13. As will be observed in 40 the drawings, when a builder chain is not present in the type of builder motion used in the particular quiller to which the invention is applied, a similar loose or lost-motion connection between the actuating part of the 45 builder motion and the guide frame is of course necessary, so that the frame can be temporarily controlled by hand independently of the gearing of the machine. When the thread guide frame has been thus depressed or over-traversed by the operation of 50 the handle 18, the continued rotation of the spindles will cause the yarn to wrap thereon below the base of the quill as will be evident from Fig. 2, so that the quills may then be 55 removed leaving the yarn attached to the spindles ready to wind at once on the fresh quill when the over-traverse device has been restored, without further attention. A 60 spring 24, applied to the sliding sleeve 22 tends to withdraw it from the fixed collar 23 and back to a position where it will not be 65 encountered by the collar during the normal traverse reciprocation of the rod 11 and hence where it will be idle and unaffected by the builder motion in its regular operation.

The handle is thus thrown down against the tension of the spring, and when released is restored and held in upright position thereby, as indicated by the dotted lines, the chain 21 being also held taut by the spring and out of the way of other parts as will be evident. All the parts of the over-traverse device are thus, in this case, held in a normally idle and inactive position by the spring 24, but yet in readiness to exert a preponderating control on the thread guide frame by the simple operation of the lever. So far as the function of the sliding sleeve 22 is concerned, it will now be evident that it is quite immaterial whether it takes the form of a part 70 actually moving or sliding on the connecting rod, or some other form, or is otherwise supported, so long as it is adapted to be advanced into operative connection or engagement with the traverse mechanism, or some 75 part connected with the thread guide frame through or by which it can depress the latter below its normal traverse. By making it as a sleeve on the rod however, as shown in the drawings, it will be apparent that complication of structure is avoided and such form and arrangement therefore constitute one of the specific features of this invention. The fixed end of the spring 24 may be attached to any suitable part of the machine, 80 but can be connected to the connecting rod itself by means of a collar 25 set-screwed thereon, this method of attachment also constituting one of the special features of the 85 invention for obvious reasons. The collar 90 25 is fastened to the rod at a point far enough along to be under tension at all times and for all positions of the traversed parts, giving and taking, with the reciprocating movement of the latter but without 95 other effect than to keep the chain 21 taut as above stated.

However, instead of employing a spring as a take-up for the over-traverse device, such 100 spring may be omitted entirely, and the 105 sleeve 22 or such part as performs the function of advancing into engagement with and depressing the traverse mechanism, may be connected with the operating handle by connections which will move such sleeve or part 110 positively in both directions and also maintain it in its normally idle condition. Thus, as shown in Fig. 5, the operating lever, here 115 marked 26, is connected with the connecting rod 11 by a rod or link 27 which has a part 27^a to engage the fixed collar 23 thereon, and is of sufficient length as indicated to place such part beyond the normal traverse of the 120 rod and collar, so that it will be wholly unaffected by the operation of the machine. 125 By throwing the lever downwardly the said part 27^a is drawn into contact with the collar 23 so as to move the connecting rod 11, to the left, a sufficient distance to over-traverse 130 the thread guides in the manner above de-

scribed, but as just stated the operating lever is otherwise idle and unaffected by the operation of the machine.

It is not to be understood that the invention is limited to the means above exemplified and explained for keeping the over-traverse device idle when not in use, for it will be evident that the essential purpose of the said device is to predominate over the builder motion and in order to depress the thread guide frame, and that such function may be accomplished whether the device moves with the traversed parts or is idle as in the case described. It is desirable that the handle or lever by which the frame is over-traversed shall project somewhat from the machine so as to be more or less conspicuous to the operator as a safeguard against inadvertent operation of the machine when the frame is depressed, which would result in a considerable waste of thread. The handle is therefore placed at one end of the quiller toward the front and adjacent to the builder motion so that it can be easily seen and also easily reached by the operative, and when thrown down will be so conspicuous, if not also so obstructive to passage around the machine as to prevent its being left in the thrown position longer than necessary. To retain the handle when thrown and hold the thread guide frame in its over-traverse position until released, a retaining means is provided, preferably upon or at the handle. In the form of Fig. 1, this means is formed by the sprocket carrier wheel 28 which guides the chain 21, cooperating with a spring-pressed bolt 29 arranged to snap automatically into a socket in the periphery of the wheel as shown in detail in Fig. 3. In the form shown in Fig. 4 the carrier wheel 28 is substituted by a fixed chain guide 32 secured to or formed as a part of the end standard and the locking means of this form comprises a bolt 31 mounted on the operating lever 26 and adapted to engage a fixed quadrant 30 to lock the parts as will be evident without explanation. Fig. 5 illustrates the same form of retaining means but various different means may of course be employed with similar effect. In any case means are provided either on the frame of the quiller or elsewhere for determining the extent of over-traverse, so that the thread guides may not be brought to a point below that indicated in the dotted lines in Fig. 2 where the thread would become entangled with the driving tape 4.

This means in Figs. 4 and 5 is represented by an abutment stop 30^a formed on the quadrant 30 and adapted to limit the movement of the lever or handle 26.

I claim:

1. In a quiller, a thread guide frame, means for normally traversing the same comprising lifter rods and levers and a connecting rod between the levers, a sleeve on such connecting rod, a lever connected to the sleeve and adapted for operation to cause the sleeve to move the rod beyond its normal traverse and means for normally maintaining said sleeve in an inoperative position with respect to the rod.

2. In a quiller, the combination with the thread guide frame, and a rod connected therewith, of a part movable parallel with the rod and adapted to engage a projection thereon to move the rod beyond its normal traverse, a spring attached to said part and to the rod and adapted to withdraw the part from engagement with the projection, and an operating member for said part subject to the tension of the said spring.

3. The combination with a traversed frame, reciprocating members comprising counterweighted lifter-levers and a connecting link, and a builder-motion operating said members to reciprocate the frame, of a manually-operated lever, an abutment on said link, and a part mounted for movement substantially parallel with the link, said part being normally separated from and adapted to contact with the abutment to shift the link and thereby depress the traversed frame through manual operation of the lever.

4. The combination with a traversed frame, reciprocating members comprising counterweighted lifter levers and a connecting link, and a builder-motion operating said members to reciprocate the frame, of a manually-operated lever, a part guided on the link for shifting the same and the lifter levers to lower the traversed frame, a chain connecting said part with the lever, and a spring take-up acting reversely to the pull of the chain.

In testimony whereof, I have signed this specification in the presence of two witnesses.

JESSE JEFFERS.
